TRAIN CONTROL SYSTEM

Herbert P. Folker, Oakland, Calif., assignor to National Safety Appliance Co., Ltd., San Francisco, Calif., a corporation of California

Application April 23, 1951, Serial No. 222,432

1 Claim. (Cl. 303—18)

This invention relates generally to pneumatic train control systems of the type adapted to effect automatic brake applications and having provision for a manual forestalling operation to prevent an automatic brake application under certain conditions.

In the past pneumatic train control systems have been employed which incorporate means on the locomotive adapted to receive a track impulse which serves to vent the main brake pipe of the pneumatic braking system of the train to thereby effect an automatic brake application. Forestalling devices such as are used with such systems incorporate a time delay mechanism having an automatic cycle which is put in operation when the engineer actuates a forestalling lever. In the event a track impulse is received by the system during the time delay afforded by the forestalling mechanism, a brake application does not occur. Should the engineer fail to make timely operation of the forestalling lever, an automatic brake application occurs in response to a track impulse, and the train is then stopped, thus requiring the engineer to thereafter carry out a restoring operation. In train control systems of the type described in Folker et al. 1,439,081 and 1,690,816 a magnetic track impulse is utilized which directly operates one of a pair of valves incorporated in a "duplex control valve," whereby a control line leading to an "automatic train stop valve" is vented to secure a brake application. A typical forestalling unit such as has been used with a system of the Folker type is shown in Patent 1,592,930, and serves to automatically shut off the line leading from the automatic stop valve to the duplex control valve, and to vent that portion of the line leading to the duplex control valve to thereby prevent operation of the same in response to a track impulse. A forestalling arrangement such as is adapted for remote operation is disclosed in Folker 2,486,271 and employs a small manually operated valve located a considerable distance from the time delay means of the forestalling unit.

In many train control systems for effecting automatic brake applications, a so-called "speed recorder or speed governor" has been employed to cause an automatic brake application when the train speed exceeds a predetermined speed limit. Such speed control means can be in the form of a speed governor which operates a switch when a predetermined speed limit has been reached, whereupon an electrical circuit is conditioned to cause an automatic brake application.

I have found that the margin of safety afforded by a system of the Folker type, together with automatic speed control as described above, can be greatly enhanced by the provision of means whereby the locomotive engineer cannot resort to a forestalling operation to prevent an automatic brake application while passing a danger zone, unless the train speed is below a value which is substantially less than the speed limit for which the speed recorder causes an automatic application. It is an object of the present invention to provide such an arrangement and to make possible such additional safety with a minimum amount of additional operating parts.

A further object of the invention is to provide an im-

proved train control system of the above character which is applicable to both remote and directly operated forestalling systems.

Additional objects and features of the present invention will appear from the following description in which the preferred embodiments have been set forth in detail in conjunction with the accompanying drawing.

Referring to the drawing:

Figure 1 is a diagrammatic view illustrating parts of a complete system incorporating the present invention.

Figure 2 is a schematic view illustrating a modification of Figure 1.

Figure 3 is a schematic view in section illustrating the forestalling means of Figure 1 and certain associated parts.

Figure 4 is a schematic view in section illustrating a modification of Figure 1 to incorporate direct operated forestalling means.

Figure 5 is a schematic view illustrating a modification of Figure 4.

The train control system illustrated in Figure 1 consists of a duplex train control valve 10 of the type adapted to be operated by a magnetic track impulse, and as disclosed for example in Letters Patents 1,439,081, 1,439,082, 1,592,930 and 1,690,816. This control valve is employed in conjunction with the release or restoring valve 11, the automatic train stop valve 12 (see 1,529,058) and the forestalling unit 13. Located at a point remote from the forestalling unit 13 there is a manually operated valve 14. In addition to these parts the system can include an air strainer 16, a double heading interlocking valve 17, and a double heading cutout cock 18. The release or restoring valve 11 and valves 17 and 18, can be substantially as shown and described in Folker 1,690,816.

The piping for the various parts mentioned above is as follows: A control pipe 20 extends from the duplex control valve 10 to the restoring valve 11. An extension 21 of the same pipe leads from the restoring valve to the shutoff valve 51. Line 22, which connects to the automatic train stop valve 12, is the brake pipe of a conventional pneumatic train braking system. Pipe 23 leads from the train stop valve 12 to the engineer's brake valve, and is equipped with a double heading cock 18. Line 24 represents a connection to the main air supply reservoir of the braking system. Line 26 is an extension of line 24 beyond the air filter 16 and connects with a time delay means of the forestalling unit as will be presently explained. Pipe 27 connects from the stop valve 12 to certain parts of the forestalling unit as indicated and in effect is an extension of the control line 21. Another pipe 28 connects stop valve 12 with the air supply pipe 26. Pipe 29 connects the restoring or release valve 11 with the interlocking valve 17, and pipe 31 connects this device to the double heading cock 18.

For a normal position of the various parts, that is a position in which the system is in condition to be responsive to a track impulse to effect an automatic brake application, the brake pipe is maintained closed against venting to the atmosphere by the stop valve 12, while air

pressure is maintained in control pipes 20 and 21, and cock 18 is open to permit control of the braking system from the engineer's cab. Pipe 28 leads to the main air reservoir and is in restricted communication with the control pipes 20 and 21. Each of the two valves in the duplex control valve 10 is retained closed magnetically,

and when the control valve passes over a track magnet, the field of which has not been neutralized by a signal current, one of the two duplex control valves (normally held closed magnetically) is opened to vent the control pipe, the particular valve operated depending upon the direction of movement of the train. The venting of control pipe 20 to the atmosphere resulting from opening of

60

one of the two control valves reduces holding pressure upon the operating diaphragm of the train stop valve 12 and as a result the valve member of the train stop valve moves to a position to cause venting of the brake pipe 22 to the atmosphere, and the valve incorporated in the same closes communication between pipes 23 and 22.

The forestalling unit incorporated in Figure 1, together with the remote forestalling valve 13, are illustrated in greater detail in Figure 3. The forestalling means illustrated consists of time delay means of the hydraulic type, including a reservoir 33 adapted to contain a quantity of suitable liquid such as oil. Restricted orifice 34 establishes communication between the lower portion of reservoir 33 and the lower portion of a vertically extending cylinder 36. A piston 37 is slidably fitted in cylinder 36 and is attached to the lower end of a rod 38. The upper end of rod 38 is attached to a member 39 which can be termed a piston valve, and which is slidably fitted in a second cylinder 41. Piston 37 is provided with suitable sealing means such as the cup leather 42, and like means such as a cup leather 43 is provided for piston 39. A compression spring 44 is shown positioned at the lower end of cylinder 36 and is adapted to be compressed when the piston 39 completes its final downward movement. The lower portion of the cylinder 41 is provided with ports 46 and 47 which are closed by the piston valve 39 for the lowermost position of the same as illustrated in Figure 3, but which are exposed for communication with the upper portion of cylinder 36 when the piston valve moves upwardly.

During a forestalling period piston 37 together with piston valve 39 are caused to move upwardly at a regulated rate by application of line pressure to the reservoir 33, and after reaching the upper limit of their travel, these members move downwardly to their initial positions. The space above piston 37 is in continuous communication with the main reservoir supply line 26.

In conjunction with the timing means there is a shutoff valve 51 and a valve actuator 52. The shutoff valve is double seated and consists of a movable valve member 53 carried by the fluted stem 54. The valve member in its one limiting position closes upon a stationary seat 56, and in its other limiting position it closes on seat 57 which surrounds stem 54. The orifice through seat 56 connects with the pipe line 27 as illustrated, and an orifice between seats 56 and 57 connects with the control line 21. In the 'normal' position of the shutoff valve as illustrated in Figure 3, lines 21 and 27 are placed in free communication. However when stem 54 is actuated to close valve member 53 upon seat 56, line 21 is vented to the atmosphere past stem 54 and line 27 is closed.

The actuator 52 can consist of a body forming a cylinder 58 and fitted with a piston 59. The space on one side of piston 59 connects with the signal whistle 61, and with pipe 62 which connects with the port 47 of the timing means. Thus when air pressure is applied to pipe (or duct) 62 the piston 59 is urged in a direction to move stem 54 and thereby close valve member 53 upon seat 56. While such pressure is applied to pipe 62 the signal whistle 61 is operated.

The forestalling unit also includes pneumatic actuator 63 and a combination vent and closure valve 64. Actuator 63 consists of a body 66 fitted with a cylinder 67. A piston 68 is fitted in cylinder 67 and is attached to the rod 69. A tube 71 is also attached to rod 69 and extends to the exterior of the device. A plunger 72 provided with a projecting stud 73 is slidably fitted within tube 71 and is yieldably urged toward projected position by the compression spring 74. Another compression spring 76 urges the piston together with the tubular member 71 toward retracted position. Duct 77 communicating with one side of piston 68 is connected by pipe 78 to the port 46 of the timing means, and also by pipe 79 to the remote valve 14.

Valve 64 consists of a valve member 81 adapted to

close upon the stationary seat 82 and carried by the stem 83. The valve stem is provided with a duct 84 which communicates with the orifice 86 formed on the outer end of the stem. The outer end of the stem loosely carries a cup 87 provided with vent openings 88, and with a seating disc 89. One side of the seat 82 is connected by pipe 91 with the line 27 leading to the automatic train stop valve. The other side of seat 82 is connected by line 92 to a duct 93 in the timing means whereby this pipe is in communication with the space in the upper part of the liquid reservoir 33.

The timing means, the pneumatic actuator 63 and the valve 64 are correlated by latching means as follows: A latch lever 94 (Figure 3) has a stationary pivotal mounting 95 and a portion of the same is interposed in the path of movement of the piston valve 39. The free end of lever 94 carries what can be termed a latch bolt 96, the lower end of which for purposes of schematic illustration is normally interposed between the aligned stud 73 and the cap 87. The arrangement of parts in this connection can be similar to that illustrated in Patent 1,592,930 (see Figures 5 and 6 of same), assuming that plunger stem 69 corresponds to the plunger stud 73 in the present instance.

The latching means functions as follows: When no pressure is being applied to the piston 68 of the pneumatic actuator 63, the parts occupy the operating positions illustrated in Figure 3, while member 81 is closed upon its seat 82 and line 92 is vented to the atmosphere through ducts 84, 86 and 88. When pneumatic pressure is applied to piston 68 by way of duct 77, movement of this piston transmits motion to the stud 73 and such motion is transmitted through the lower end of latch bolt 96, to close cap 87 upon orifice 86 and to move the valve member 81 to open position with respect to seat 82. Thereafter when piston valve 39 strikes latch lever 94 and swings the same upwardly a limited distance, latch bolt 96 is retracted from its normal position between stud 73 and cap 87, whereby valve member 81 is permitted to close and cap 87 permitted to move to open the venting orifice 86. This initiates a downward movement of the piston valve 39, and after piston 37 has completed its downward movement, pneumatic pressure upon piston 68 is relieved whereby this piston is permitted to return to its initial position under the urge of compression spring 76, thereby enabling the latch bolt 96 to again drop down into its former position illustrated in Figure 3.

The remote valve 14 consists of a body 101 provided with a valve member 102 normally urged by spring 103 against the stationary seat 104. A fluted stem 106 is attached to the valve member and is engaged by the lower end of the operating rod 107. The operating rod extends to the exterior of the valve body where it is provided with an operating button 108. Within the body the operating rod is attached to a piston 109 fitted in the cylinder 111. One side of the piston 109 is vented to the atmosphere through the space about rod 107. The other side is normally in communication with the outflow passage 112. The inlet passage 113 of the valve is connected to the main reservoir supply pipe 114 while the outflow passage 112 connects with the line 79, which in turn connects with the pneumatic actuator 63 and with the timing means.

The system insofar as described above is the same as disclosed in my Patent 2,486,271. In conjunction with this system I have shown a speed recorder 116. This speed recorder can be of the type manufactured by Barco Manufacturing Co., Chicago, Illinois, and includes centrifugal governing means operatively connected to a wheel of the train and serving to operate an electrical switch when the train speed exceeds the limit for which the instrument is set. In a typical instance this limiting speed may be 78 M. P. H. In addition to the regular speed limit switch, I provide a second electrical switch 117 which is likewise arranged to be operated by the cen-

trifugal governor of the instrument, and which can be set to be operated when the speed exceeds a somewhat lower value, such as 40 M. P. H. Switch 117 is shown connected to control an electrical circuit including the battery 118 or other source of current, and the operating solenoid 119 is for the valve 121. Pipe 122 serves to connect this valve with the pipe 79, which connects the remote valve 14 with the timing means. Valve 121 when opened by energizing the solenoid 119 vents to the atmosphere.

Operation of the system described above is as follows: Assuming that the system is in normal operation ready to receive a track impulse, and that the double heading cock 18 is turned to open position to permit control from the engineer's cab as desired, the two valves of the duplex control valve 10 are in closed position and are retained closed against the pressure of air in control pipe 20 by the magnetic field of a permanent magnet as described in Patent 1,548,593. The parts of the forestalling unit are substantially in the position as illustrated in Figures 1 and 3, and the double seated shutoff valve 51 is in the position illustrated whereby pipes 21 and 27 are in free communication. By virtue of pressure maintained in pipe 27 the valve member of the automatic train stop valve 12 is maintained in such a position that the valve means of the same maintains pipe 22 in non-venting condition. At the same time however pipes 20, 21 and 27 are in restricted communication with the main source of air supply through the train stop valve.

Assuming that the train is proceeding at a speed below the limiting speed for which the speed recorder 116 is set (e. g. 78 M. P. H.) and that a track impulse is received by the duplex control valve without operation of the forestalling unit, line 20 is vented to the atmosphere by the opening of one of the valve members of the duplex control valve, and this serves to vent line 27 from the stop valve 12, whereby the train stop valve automatically operates to vent the brake pipe 22 to the atmosphere. This serves to effect an automatic brake application. To restore the system to normal operation the engineer moves the handle of the restoring valve 11 to the restoring position, whereby pipe 20 is vented to the atmosphere and temporarily disconnected from pipe 21, and pipe 21 is connected to pipe 29 and thereby vented to the atmosphere through the interlocking valve 17. This retains the brakes applied and permits the pressure in pipe 20 to drop to atmospheric, whereby the valve member of the duplex control valve which has been actuated to open position, is permitted to return to closed position. Thereafter the handle of the restoring valve 11 is returned to normal position and pipe 20 is reconnected with pipe 21.

Assuming that the engineer is alert and carries out a forestalling operation to prevent brake application by a track impulse, button 108 of the remote forestalling valve 14 is depressed whereby valve 102 is unseated to permit application of air pressure from the main supply through pipe 79 to the pneumatic actuator 63. Operation of the actuator 63 serves to close the venting orifice 86 and unseat the valve member 81, whereby pressure from line 27 through line 91 is applied through pipe or duct 92 and duct 93 of the timing means to the space above the liquid in the reservoir 33. Liquid from reservoir 33 now commences to flow through the restricted orifice 34 to the space beneath the piston 37. The initial movement of this piston is aided by the compression spring 44. Piston valve 39 moves upwardly within cylinder 41, and when port 46 is exposed this port together with line 78 is placed in free communication with the space above the piston 37. In connection with the upward movement of piston 37 the full pressure of the main reservoir supply is applied to the space above the piston 37. However the upper area of piston 37 minus the upper area of piston 39 is less than the bottom area to which the liquid pressure is applied. Therefore a differential force acts to urge the piston upwardly. Exposure of port 46 to the space

above the piston applies a full main reservoir pressure to the pipe 78, to pipe 79 and to the pneumatic actuator 63. The pressure thus applied to the actuator can be termed the holding pressure and thereafter the operator

5 may release the button 108, without interfering with automatic continuation of the forestalling cycle. Release of button 108 permits it to raise to an elevated position above the normal position shown in Figure 3 due to the fact that piston 109 is urged upwardly by pressure applied 10 to passage 112. Valve 102 is also returned to its normal position shown in Figure 3 by action of spring 103.

Simultaneously with exposure of port 46 the port 47 is likewise exposed to the line pressure existing in the upper portion of cylinder 36. Therefore main reservoir pressure 15 is applied through pipe 62 to the pneumatic operator 52 whereby the piston 59 of this operator operates the shutoff valve 51 to close the valve member 53 upon seat 56. Thus shortly after the commencement of the forestalling period the control line 21 is shut off from communication 20 with the remainder of the control line 27, and likewise that part of the control line leading to the duplex control valve by way of pipe 21 is vented to the atmosphere. As a result a track impulse will not operate either one of the two control valves.

25 The piston 37 moves upwardly at a predetermined speed and when it reaches substantially the upper limit of its travel, piston valve 39 strikes the latch lever 94 with the result that latch bolt 96 as diagrammatically illustrated is effectively withdrawn from between stud 73 and the cap

30 37 (ignoring for the sake of diagrammatic illustration the additional lever 85 shown in Patent 1,592,930 which would customarily be used in place of a single latch bolt). This serves as a motion transmitting element to permit closure of valve member 81 and to cause venting of line 92

35 through orifice 86. Reduction of pressure upon the liquid in the reservoir 33 to atmospheric results in downward movement of the piston 37 under the urge of air pressure from the main reservoir supply. During the last portion of the downward travel of the piston 37, communication

40 between ports 46 and 47 and line 26 is interrupted by seal 43 and the pressure in both 46 and 47 is reduced to atmospheric because of leakage past piston 39. Thus the shutoff valve 51 is permitted to open to re-establish communication

45 between pipes 21 and 27. Also air is no longer supplied from line 114 to pneumatic actuator 63, and the closure valve 64 is therefore permitted to open to vent pipe 92 to the atmosphere through orifice 86. Button 108 is therefore permitted to drop down to its normal position shown in Figure 3 by gravity. This serves to 50 indicate to the operator that the forestalling period has ended.

Assuming now that the train enters a danger zone at a speed sufficient to cause the switch 117 to be operated by the speed recorder and governor 116 (e. g. above 40

55 M. P. H.) the open condition of valve 121 serves to automatically make it impossible for the engineer to avoid a brake application by a track impulse, by operating the forestalling valve. Thus if the engineer should operate the remote forestalling valve 14, under such conditions,

60 the discharge side of the valve 14 would be vented to the atmosphere through pipe 122, and insufficient pressure would exist in pipe 79 to operate the pneumatic actuator 63. As a result the combination vent and closure valve 64 would not be operated to cause pressure to be applied

65 to the timing means through pipe 92. Thus upon receipt of a track impulse by the duplex control valve 10, an automatic brake application would occur irrespective of whether or not the engineer had attempted to prevent such application by operating the remote forestalling valve 14.

70 It will be evident that my invention provides an added factor of safety in automatic train control systems, because it places a penalty upon entering a danger zone at 75 a speed above that which would normally be considered

safe under such conditions. The penalty is the same as that which has been described in the aforementioned prior patents, namely that after the train has been stopped by an automatic brake application, it is necessary for the engineer to proceed with a restoring operation, which involves descending from his cab to operate the restoring valve 11. My system does not alter the other functions for the speed recorder 116, namely to cause an automatic brake application in the event the train at any time exceeds a safe limit such as 78 M. P. H.

Another manner of connecting the valve 121 is shown in Figure 2. In this instance the valve 121 has its inlet side connected to the pipe 114, which supplies air pressure to the forestalling valve 14. With this arrangement when switch 117 is closed solenoid 119 is energized to close valve 121, and this serves to interrupt supply of air to the valve 14. Thus when the valve 14 is operated manually no air pressure is transmitted through line 79 to cause operation of the forestalling means.

Figure 4 illustrates another embodiment of the invention which incorporates a direct manually operated forestalling means. The valve 14 is omitted, and in place of the pneumatic actuator 63, there is a hand lever 126 mounted upon the rotatable shaft 127. As diagrammatically illustrated the shaft carries a spring pressed lug 128 adapted to engage and transmit force to the lower end of the latch bolt 129. Thus when the hand lever is turned clockwise 270° from the position viewed in Figure 4, the cap 87 of the valve 64 is operated whereby the valve member 81 is unseated. This operation is the same as when the pneumatic actuator 63 of Figure 1 is operated by air pressure, and it effects commencement of a forestalling cycle. Latch bolt 129 is pivotally attached to the latch bolt 131, corresponding to the latch arm 94 of Figure 1. When the piston 37 reaches the upper end of its travel latch lever 131 is operated to retract the bolt 129, with the result that valve 64 is permitted to return to its normal initial position, and the forestalling lever 126 permitted to return to its initial position as illustrated. In actual practice the parts just described can be similar to corresponding parts disclosed in Patent 1,592,930.

The solenoid operated valve 121 is connected by pipe 122 with the pipe 92. Thus when the valve 121 is opened by closing of the governor operated switch 117, pipe 92 is continuously vented, and therefore operation of the forestalling lever 126 cannot cause a build-up of pressure in pipe 92 to operate the time delay means. Thus this modified system functions in substantially the same manner as the remote forestalling system described with reference to Figure 1.

Figure 5 illustrates a modification of the arrangement described above with reference to Figure 4. In this instance the pipe 122 leading from the solenoid operated valve 121 is connected to the pipe 62. Thus when the switch 117 is closed to open the solenoid valve 121, pipe 122 is vented together with pipe 62, whereby no pressure can be developed in pipe 62 for operation of the valve actuator 52. Thus if an engineer should attempt to defeat an automatic brake application when entering a danger zone at an excessive speed, (e. g. above 40 M. P. H.) upward movement of piston 37 to uncover the passage 47 does not result in operation of the pneumatic operator 52, and therefore the shutoff valve 51 is not operated. Without operation of the shutoff valve 51, the control line 21 remains in communication with the line 27, and that part of the control line leading to the duplex control valve is not vented to the atmosphere. As a result a track impulse causes an automatic brake application.

References have been made to the operation of the solenoid operated valve 121 responsive to the closing of the switch 117. As is well understood by electrical engineers, the circuit can be arranged to obtain the desired operation when switch 117 is opened. Also it is possible to substitute pneumatic or other type of control means for the electrical circuit arrangement. For ex-

ample, I can employ a valve having a pneumatic operator in place of a solenoid and such a valve can have its operator connected to a source of air pressure controlled by a pilot valve which is substituted for the switch 117.

It will be evident that my invention is capable of additional embodiments and variations. Thus if desired either the remotely operated or direct manually operated forestalling means may be employed in conjunction with a line charger in the manner disclosed and claimed in my Patent 2,486,271.

It will be evident that my invention can be incorporated in the pneumatic train control system of the Folker type with a minimum amount of additional equipment. When an installation is made as described above, certain hazards in the operation of the train are definitely minimized. The engineer is forced to enter danger zones at a speed well below the maximum limiting speed for which the speed recorder is set, and only when the train is proceeding at such a safe speed, can the forestalling means be effective.

I claim:

In a pneumatic train braking system, a control valve adapted to be actuated by a track impulse, a control line connected to said control valve whereby said line is vented upon actuation of the control valve by a track impulse, an automatic train stop valve connected to said control line for causing a brake application when the control line is vented, a manually initiated forestalling unit, said unit including fluid pressure operated timing means having a timing cycle and a shutoff valve connected to the control line, fluid pressure operated means having a fluid pressure connection to the forestalling unit and arranged, when actuated by fluid pressure from said forestalling unit during a timing cycle, to move said shutoff valve from a first to a second operating position, said shutoff valve in its first operating position establishing communication between the control valve and the automatic train stop valve through the control line and in its second operating position interrupting such communication and venting to the atmosphere that portion of the control line extending from the shutoff valve to the control valve, said shutoff valve being so arranged that fluid pressure in the control line serves to urge the shutoff valve toward said first operating position, manual initiation of a timing cycle of the forestalling unit when the train is proceeding at or below a predetermined safe train speed and before receipt of a track impulse serving to prevent an automatic brake application when the track impulse is received, and control means responsive to a train speed in excess of a predetermined safe speed and arranged to prevent actuation of said fluid pressure operated means to position said shutoff valve in said second position whereby under such condition of excessive train speed manual initiation of the forestalling unit timing cycle does not prevent an automatic brake application by a subsequently received track impulse, and in which a remote forestalling valve is provided having a pneumatic connection to the forestalling unit, said forestalling valve when manually actuated serving to apply fluid pressure to the forestalling unit to initiate a forestalling unit timing cycle, and in which said control means responsive to a train speed in excess of a predetermined safe speed includes a valve having a fluid connection to the connection between the forestalling valve and the forestalling unit and serving to vent said last connection when the train speed is in excess of a predetermined safe speed.
